UNITED STATES PATENT OFFICE.

MATTHEW W. RYAN, OF NEW YORK, N. Y.

DESIGN FOR CRETONNE OR OTHER TEXTILE FABRIC.

49,833.

Specification for Design.

Patented Oct. 31, 1916.

Application filed July 29, 1916. Serial No. 112,179. Term of patent 3½ years.

To all whom it may concern:

Be it known that I, MATTHEW W. RYAN, a citizen of the United States of America, residing in the city of New York, borough of Manhattan, county and State of New York, have invented a new, original and ornamental Design for Cretonnes or other Textile Fabrics, of which the following is a specification, reference being had to the accompanying drawing, forming a part thereof, wherein the figure represents one repeat of a design as applied to the fabric.

What I claim and desire to secure by Letters Patent is:

The ornamental design for a cretonne or other textile fabric consisting of a design substantially as shown.

MATTHEW W. RYAN.
